(57) **CLAIM**

The ornamental design for a J-shaped flash drive, as shown and described.

DESCRIPTION

FIG. 1 is a front view of a J-shaped flash drive showing our new design;

FIG. 2 is a rear view thereof;

FIG. 3 is a right side view thereof, the left side being a mirror image thereto;

FIG. 4 is a bottom view thereof;

FIG. 5 is a top view thereof;

FIG. 6 is a rear top left perspective view thereof;

FIG. 7 is a rear bottom left perspective view thereof;

FIG. 8 is a front bottom left perspective view thereof;

FIG. 9 is a front top left perspective view thereof;

FIG. 10 is a right side view thereof, shown in an environment of use; and,

FIG. 11 is a front side view thereof shown in a second environment of use.

The broken lines showing the connectors in FIGS. 1–11 represent portions of the article which form no part of the claimed design. The broken lines showing the smart phone in FIG. 10 and the laptop in FIG. 11 are included for the purpose of illustrating environmental structure and form no part of the claimed design.
